(57) **CLAIM**

The ornamental design for a frame for a drying shelf, as shown and described.

DESCRIPTION

FIG. 1 is a perspective view of a frame for a drying shelf with the hooks shown in broken lines showing our new design;

FIG. 2 is a top view thereof;

FIG. 3 is a bottom view thereof with the magnets on the brackets and the recesses in the elbow joints shown in broken lines;

FIG. 4 is a left side elevation view with the hooks shown in broken lines, the right side-being a mirror image thereof;

FIG. 5 is a front elevation view thereof with the hooks shown in the broken lines; and,

FIG. 6 is a rear elevation view thereof with the magnets on the brackets and the recesses in the elbow joints shown in broken lines.

The broken lines shown in the drawings are for illustrative purposes only and form no part of the claimed design.
